FIRE ALARM DEVICE

Curt J. Rohland, Seekonk, Mass., assignor to
 Signal Engineering & Manufacturing Company,
 New York, N. Y., a corporation of Massachusetts

Application October 30, 1931, Serial No. 572,100

6 Claims. (Cl. 185—37)

The present invention relates to fire alarm systems and more particularly to the despatching mechanism for a fire alarm box by which a given code signal is sent to fire headquarters, or broadcasted to separate stations.

In apparatus of this type, as heretofore constructed, the despatching mechanism of a call box is usually set in operation by a hand lever, movement of the lever causing a spring to be wound, after which said spring actuates the despatching mechanism upon release of the lever. Should the person turning in the alarm hold the lever at the end of its movement without releasing it, the mechanism is not allowed to operate and no signal is sent. On the other hand, should the person turning in the alarm attempt to actuate the lever repeatedly, no results being immediately apparent from the first movement of the lever, an incorrect signal is liable to be transmitted, especially when the despatching mechanism is sending a code signal indicating the location of the box.

With the above objections of prior mechanisms in mind, one of the objects of the present invention is to provide a despatching mechanism which is set in operation immediately upon movement of the lever, said mechanism being independent of said lever after having been set in operation, and operating independently of the position of said lever.

According to the present invention, the manually operated actuating lever is arranged to be easily turned by a pull away from the box face and to be released automatically from operative connection with said despatching mechanism after said lever has been moved through the predetermined path, thereby breaking the connection between said lever and the despatching mechanism so that said despatching mechanism after having been set in operation, continues to operate independently of the position of the lever, until the mechanism has substantially completed its operation. The connection between said lever and the despatching mechanism is so arranged that the members cannot again be operatively connected until at least one complete signal has been sent by said mechanism. The actuating lever is automatically returned to its original position after release, so that when the operation of the despatching mechanism is completed, said lever is again in position to be connected to said mechanism and in a position for again setting said mechanism in operation when said lever is again actuated, said operative connection being

impossible until the operation of the despatching mechanism is substantially completed. Other objects and advantages will appear from the following detailed description taken in connection with the accompanying drawing, in which:—

Fig. 1 is an elevation view of a fire alarm box showing the actuating lever.

Fig. 2 is a front view of the despatching mechanism within the box.

Fig. 3 is a fragmentary side elevation of the despatching mechanism, parts being broken away to show the construction thereof.

Fig. 4 is a view corresponding to Fig. 3, the parts being in the position in which the actuating lever is released from the despatching mechanism.

Fig. 5 is a fragmentary view, illustrating the position of the operating handle.

Like reference characters refer to like parts throughout the drawing.

Referring particularly to the drawing, the fire alarm box 1 is provided with a cover or door 2 hingedly mounted at 3 on said box. Within the box is located the usual despatching mechanism shown in Fig. 2 arranged to be actuated by a lever 4 which is accessible from the front of the box when the door 2 is open and which, as indicated in Fig. 1, is moved downwardly and upwardly with respect to the box, through a predetermined angle.

The despatching mechanism is of the usual construction having a spring, not shown, contained within a case 5 carried by the frame 6 of the despatching mechanism. The spring which is mounted on a shaft 7 is arranged to be coiled in response to forward and downward swinging movement of the lever 4 through interengagement of a gear 8 on the shaft 7 with a sector gear 10 on the shaft 11, the lever 4 being mounted on the latter shaft. Rotation of the lever 4 through its predetermined angular path rotates the gear 10 through the same angle, thereby winding the spring within the case 5, so that upon release of the lever 4 at the end of its movement, the tension of the spring actuates the despatching mechanism to send the predetermined signal to fire headquarters.

According to the present invention, a releasable connection is provided between the lever 4 and the gear 10, so that as the lever reaches the end of its predetermined movement, the gear 10 is released therefrom and the despatching mechanism may operate independently of the position of said lever. As best shown in Figs. 3 and 4, the gear 10, which is rotatably mounted on the shaft 11, carries thereon a link 12 pivotally mounted on

a stud 13 attached to said gear and spaced from the shaft 11. The link 12 carries a projecting tooth 14 which is adapted to engage with a tooth 15 formed on a collar 16 rigidly secured to the shaft 11. In the normal position of the lever 4, the teeth 14 and 15 are in the position of Fig. 3, so that as the shaft 11 is rotated counterclockwise (as viewed in Fig. 3), the tooth 15 rotates therewith and engages with the tooth 14 on the link 12, as shown in dotted lines, thereby providing a positive driving connection from the lever 4 to the gear 10. As the shaft 11 is rotated, the gear 10 rotates as a unit with said shaft to turn the shaft 7 and coil the spring prior to setting the 15 despaching mechanism in operation.

As the lever 4 reaches the end of its downward movement, as indicated in dotted lines in Fig. 4, the gear and shaft assume a position in which the driving connection between the lever and the gear 10 has been broken. Just before the lever 4 reaches the end of its downward movement, when said lever and gear are still positively connected, the downwardly extending end 17 of the link 12 engages a stud 18 mounted on the frame 6 of the despaching mechanism, whereby, upon continued counterclockwise rotation of the shaft 11, the tooth 14 is withdrawn from engagement with the tooth 15 on the collar 16. In this position, the gear 10 may rotate clockwise, independently of the position of the shaft 11, so that the despaching mechanism operates without respect to the location of the lever 4. As the despaching mechanism continues to operate in response to the driving spring, the shaft 7 slowly turns in the opposite direction and the gear 10 rotates clockwise, until it again assumes the position shown in Fig. 3 at the completion of the operation of the despaching mechanism. During the clockwise rotation of said gear 10, a spring 20 rigidly mounted on the end of the stud 13 on which the link 12 is mounted engages a pin 21 on said link 12, thereby exerting a force tending to turn the link 12 clockwise about the stud 13. This turning of the link 12 is limited by engagement of a surface 22 on said link 12 with the collar 16, as shown in Fig. 4, the degree of rotation of said link being only sufficient to separate the teeth 14 and 15 radially and prevent said teeth from interlocking as the gear 10 rotates clockwise.

As the mechanism again assumes the position shown in Fig. 3, the link 12 is urged into operative position, so that the tooth 14 may interlock with the tooth 15 on the collar 16, by the same spring 20. In the position shown in Fig. 3, the end of the spring 20 is engaged by the stud 18, so that said spring is moved into engagement with a second pin 23 carried by the link 12. The link 12 is turned counterclockwise in response to the spring, thus bringing the teeth 14 and 15 into the operative position of Fig. 3. The spring 20 is aided in this movement by the weight of the link 12, which as shown tends to swing the link 12 counterclockwise. A coil spring 24 encircles the shaft 11, one end of said spring engaging the collar 16 and the other end engaging a portion of the frame 6, thereby tending to swing the shaft with the lever arm 4 to the position shown in Figs. 1 and 2, immediately upon release of said lever. Therefore, the lever 4 is always in position for despaching another signal when the despaching mechanism has completed its operation.

The arrangement of spring 20 is such that even should the lever arm 4 be swung downwardly only part way and then released, the link 12 is immediately swung clockwise by the pressure of the

spring on the pin 21 to separate the interlocking teeth 14 and 15. This disengagement of the teeth permits the despaching mechanism to operate for at least a portion of its cycle, the spring 20 holding the link 12 in inoperative position so that subsequent movement of the lever arm 4 is ineffective until the despaching mechanism has completed its operation. While pressure is maintained on the lever arm 4 during the movement of said arm downwardly, the friction between the 10 interlocking teeth 14 and 15 is sufficient to overcome the effect of the spring 20; otherwise the teeth are separated either at the end of the movement of the lever arm by engagement of the link 12 and stud 18, or by release of the lever arm before said arm reaches the downward limit of its movement, the spring 24 then returning the lever arm to original position.

From the foregoing it will be apparent that the despaching mechanism is always fully wound by 20 movement of the lever 4 forwardly and downwardly (Figs. 1 and 2) until the teeth 14 and 15 which connect the lever arm to the spring winding mechanism, are moved out of engagement by the stud 18 at the end of the lever movement. 25 From this point, the operation of the despaching mechanism carries on, irrespective of the position of the lever 4 and whether or not it is released, the operation continuing until said spring is substantially unwound and the mechanism assumes 30 the original position shown in Fig. 3 in readiness for another winding of the spring. Should the lever 4 be turned while the spring is still unwinding, it will have no effect on the mechanism until the teeth 14 and 15 automatically assume their 35 operative position at the completion of an operating cycle of the despaching mechanism. Thus, when a code is being transmitted, it cannot be interrupted by turning the lever, repeatedly, since the lever is entirely disconnected from the wind- 40 ing gear 10 until the cycle is completed.

As illustrative of the utility of the invention, the essential elements of one form of despaching or code sending mechanism are shown in Figs. 2 and 3. In this mechanism, the shaft 7 which is turned by the winding spring carries a gear 25 in mesh with a pinion 26 mounted on a shaft 27. As best shown in Fig. 2, the shaft 27 extends beyond the left hand frame 6 and carries a code disk 28 adapted to cooperate with contacts 29 and 30 50 mounted on a bracket 31 and insulated from each other. Part of the code disk 28 is shown as projecting below the broken away portion of the frame 6 in Fig. 3, the disk 28 carrying projections 28a adapted to determine a code signal in accordance with the spacing therebetween. The normally engaged contacts 29 and 30 extend to a point below the disk 28 and one contact carries an operating portion 32 of insulating material which is adapted to be engaged by the projections 60 28a on the disk when the latter rotates to intermittently separate the contacts.

Each revolution of the disk 28 is therefore adapted to make and break a circuit under the control of the contacts 29 and 30, in accordance 65 with the arrangement of the code determining projections 28a, and preferably the ratio between the gear 25 and pinion 26 is such that one complete winding of the spring by pulling down the lever 2 all the way is sufficient to turn the shaft 70 27 and its code disk 28 through several complete revolutions. In other words, moving the lever 4 from its normal position shown in Fig. 1 to the dotted line position of Fig. 4 initiates the sending of a complete cycle of signals in accordance with 75

a code, irrespective of whether the handle 4 is released or not, and the signal cycle is completed, without interruption or disturbance, even though the handle be removed repeatedly during the 5 sending of the signals. On the other hand, should a person in the excitement of the moment of sending an alarm pull down the handle 4 only part of the way and then release it, the gear 10 will be turned far enough to partially wind the 10 spring and thereby cause the turning of the code disk 28 through at least one revolution to sound the code number once at fire headquarters, or throughout the system under control.

I claim,

- 15 1. In an alarm device, an actuating mechanism for the code sending element of a despatching mechanism, a gear connected to said actuating mechanism for energizing the latter in response to rocking movement of said gear, a manually actuated lever, a shaft to which said lever is secured, the latter being turnable in response to actuation of the lever, a link carried by said gear, cooperating teeth on said link and shaft for interengagement whereby turning movement 20 of the gear is procured in response to movement of the lever, means acting on said link independently of said lever for releasing the connection between said teeth after the lever has been moved a predetermined amount in one direction even 25 though said lever is still held manually, and means for maintaining said link and lever in disconnected relation independently of the position of the lever until the actuating mechanism has substantially completed its operation.
- 30 2. In an alarm device, an actuating mechanism for the code sending element of a despatching mechanism, a gear connected to said actuating mechanism for energizing the latter in response to rocking movement of said gear, a manually actuated lever, a shaft to which said lever is secured, the latter being turnable in response to actuation of the lever, a link carried by said gear, cooperating teeth on said link and shaft for interengagement whereby turning movement 35 of the gear is procured in response to movement of the lever, means acting on said link independently of said lever for releasing the connection between said teeth after the lever has been moved a predetermined amount in one direction even 40 though said lever is still held manually, and means for returning said lever to original position when said lever is released, and means for maintaining said link and lever in disconnected relation independently of the position of said 45 lever until the actuating mechanism has substantially completed its operation.
- 50 3. In an alarm device, an actuating mechanism for the code sending element of a despatching mechanism, a gear connected to said actuating mechanism for energizing the latter in response to turning movement of said gear, a shaft on which said gear is turnable, a manually actuated lever secured to said shaft for turning said shaft in response to movement of said lever, a link pivotally mounted on said gear and having a tooth thereon, a tooth on said shaft in opposed relation to the tooth on said link, means for yieldably maintaining said teeth in interengagement, and means separate from said shaft and 55 lever for pivotally turning said link for disen-

gaging said teeth after said lever has been turned a predetermined amount and is still held manually, to release said gear and thereby provide for operation of the actuating mechanism.

4. In an alarm device, an actuating mechanism for the code sending element of a despatching mechanism, a gear connected to said actuating mechanism for energizing the latter in response to turning movement of said gear, a shaft on which said gear is turnable, a manually actuated lever secured to said shaft for turning said shaft in response to movement of said lever, a link pivotally mounted on said gear and having a tooth thereon, a tooth on said shaft in opposed relation to the tooth on said link, means for yieldably maintaining said teeth in interengagement, and means for pivotally turning said link for disengaging said teeth after said lever has been turned a predetermined amount and is still held manually, to release said gear and thereby provide for operation of the actuating mechanism, said yieldable means also serving to maintain said teeth in separated relation after they have been disengaged and until the gear has returned substantially to its original position.

5. In an alarm device, an actuating mechanism for the code sending element of a despatching mechanism, a gear connected to said actuating mechanism for energizing the latter in response to turning movement of said gear, a manually operable lever mounted to turn with a rotatable shaft, a link pivotally mounted on said gear, cooperating teeth on said link and on said lever shaft respectively, which teeth when in engagement are adapted to impart turning movement of said lever to said gear, a stationary stop offset from the axis of said lever shaft for positively disengaging said teeth after the lever has been turned a predetermined amount in one direction, even though said lever is still held manually, and means for maintaining the teeth on said link and lever disengaged independently of the position of said lever, until the actuating mechanism has substantially completed its operation.

6. In an alarm device, an actuating mechanism for the code sending element of a despatching mechanism, a gear connected to said actuating mechanism for energizing the latter in response to turning movement of said gear, a manually operable lever mounted to turn with a rotatable shaft, a link pivotally mounted on said gear, cooperating teeth on said link and on said lever shaft respectively, which teeth when in engagement are adapted to impart turning movement of said lever to said gear, a stationary stop offset from the axis of said lever shaft for positively disengaging said teeth after the lever has been turned a predetermined amount in one direction, even though said lever is still held manually, and means for maintaining the teeth on said link and lever disengaged independently of the position of said lever, until the actuating mechanism has substantially completed its operation, with said stop also serving to move the tooth on said link into operative relation with respect to the tooth on said shaft upon the return of said gear to its initial position following operation of said actuating mechanism.
